UNITED STATES PATENT OFFICE

2,618,415

DISPENSING CLOSURE COMPOSED OF TWO
TELESCOPING PARTS RELATIVELY MOV-
ABLE BETWEEN TWO POSITIONS BY SNAP
ACTION

Herbert B. Ellefson, Oklahoma City, Okla.

Application July 16, 1948, Serial No. 39,121

2 Claims. (Cl. 222—499)

1

This invention relates to improvements in dispensing closure caps for collapsible paste tubes and more particularly to an improved dispensing cap to be substituted for the screw cap originally provided with such tubes and remain permanently attached to the tube until the tube contents are entirely dispensed.

The inconvenience of the screw-threaded closure caps ordinarily provided on collapsible paste tubes is well known, such caps requiring time and skill to remove and replace them and being frequently lost or forgotten. Such conventional caps also frequently come off the tubes when the tubes are packed in baggage for traveling, allowing the contents of the tubes to spill, and usually cause the extrusion and wastage of a small amount of the tube contents each time one of them is replaced on a tube.

It is among the objects of the present invention to provide an improved dispensing closure cap for collapsible paste tubes to replace the screw caps conventionally provided for closing such tubes which dispensing closure cap is permanently retained on a collapsible tube while the tube contents are being used, but may be removed, if desired, when the tube contents are exhausted and installed on a new tube, which is opened and closed by a simple reciprocating movement of one of its parts in a manner which requires an insignificant amount of time and so little skill that it can be opened and closed by a small child, that utilizes a minimum number of simple parts formed of inexpensive materials, provides a tight and secure closure for the tube, and is durable in construction, economical to manufacture, and neat and attractive in appearance.

Other objects and advantages will become apparent from a consideration of the following description and the appended claims in conjunction with the accompanying drawing, wherein:

Figure 1 is a longitudinal medial cross-section of a dispensing closure cap illustrative of the invention shown attached to the screw-threaded neck of a conventional collapsible paste tube;

Figure 2 is a view similar to Figure 1 showing the dispensing cap section on a plane substantially at right angles to the cross-sectional plane of Figure 1 and shown partly in elevation;

Figure 3 is an elevation of the outer member of the improved closure cap illustrated in Figures 1 and 2;

Figure 4 is an elevation of the inner member of the improved closure cap.

With continued reference to the drawing, and

particularly to Figures 1 to 4 inclusive, the numeral 10 generally designates a conventional, collapsible paste tube having a somewhat conical end wall 11 from the apex of which extends the externally screw-threaded neck or spout 12 of the tube. A conventional screw cap, not illustrated, is normally applied to the neck 12 to close the paste dispensing opening through the neck.

10 In accordance with the present invention, the screw cap conventionally provided to close the spout 12 of the tube is discarded and the improved dispensing closure cap, generally indicated at 13, is substituted therefor and left permanently attached to the tube neck or spout until the contents of the tube have been exhausted.

The improved dispensing cap comprises an inner body 14 of cylindrical shape having one open end and a semi-spherical end wall at the opposite end. This body 14 is provided adjacent its open end with an internal annular recess 15 within which is secured a cylindrical sleeve 16 of resilient material adapted to be threaded onto the external screw threads of the tube neck 12. This sleeve 16 may be made of relatively soft, resilient material, such as rubber, and left entirely unthreaded so that it can be threaded upon any of the various types of threads provided by different tube manufacturers, or it can be made of a somewhat harder material and provided with threads adapted to receive the threads of a particular type of tube, or, in some cases may be dispensed with entirely. If the sleeve 16 is omitted the body 14 will be somewhat thickened adjacent its open end and provided with internal screw threads adapted to receive the threads of tubes of a particular type of manufacture in the event the dispensing caps are provided for a particular product.

40 Externally the body 14 is provided with two diametrically-opposed, longitudinally-extending grooves 17 which extend from the open end of the body for a portion of the length of the cylindrical part of the body, and a respective rounded abutment 18 is provided in each of these grooves intermediate the length thereof. Midway between the grooves 17 the inner body 14 is provided with a longitudinally-extending ridge 19 extending from the open end of the body and beyond the inner end of this ridge with a rectangular outlet aperture 20. The inner body 14 is preferably formed of a suitable synthetic resin plastic material for economy in manufacture, durability in use and attractiveness of appearance, but other materials, such as metal or hard rubber may be

used if found to be more practical or economical.

The outer body 21 has a shape similar to and slidably receives the inner body 14, but preferably has a wall thickness materially less than the wall thickness of the inner body. This outer body is provided with a rectangular outlet aperture 22 of substantially the same size and shape as the aperture 20 of the inner body and so positioned that the two apertures 20 and 22 are out of registry with each other, as clearly illustrated in Figure 2, when the outer body is in its inward or closing position relative to the inner body. When the outer body is pulled outwardly of the inner body to its outer limiting position the two apertures 20 and 22 are in registry with each other so that the contents of the tube 19 can be forced out through these registering apertures by applying pressure to the body of the collapsible tube. In addition to the aperture 22 the outer body is provided with a longitudinally-extending slot 23 between the aperture 22 and the open end of the outer body which slot receives the ridge 19 on the inner body and this slot and ridge maintain the two bodies against relative rotation while permitting sliding movements of the outer body on the inner body in both directions. The outer body is also provided with two rounded indentations 24 near the open end thereof which indentations are diametrically opposed and in alignment with the grooves 17 of the inner body and provide detents cooperating with the inner body abutments 18. When the outer body is in its inner or closing position relative to the inner body the detents 24 bear against the sides of the rounded abutments 18 adjacent the open end of the inner body to resiliently hold the outer body in its inner or closing position relative to the inner body. When the outer body is pulled outwardly the detents 24 pass over the abutments 18 and spring into the recesses between the sides of these abutments opposite the open end of the inner body and the inner ends of the grooves 17 to resiliently hold the outer body in its outer or cap-opening position relative to the inner body. The inner ends of the grooves 17 are provided with sharp shoulders which frictionally engage the detents 24 to effectively prevent separation of the two bodies 14 and 21. The outer body 21 is also preferably formed of a suitable synthetic resin plastic material having the necessary resiliency or flexibility to provide for the resilient operation of the detents 24 in cooperation with the abutments 18, as explained above.

What is claimed is:

1. A dispensing closure cap for a collapsible paste tube having a threaded dispensing neck, comprising, an inner member having a closed end and an open end, a resilient adapter engaged on the neck of the tube and means mounting the

open end of the inner member on said adapter, said inner member having a discharge opening, an outer member cooperatively arranged in telescoping fashion on the inner member and having a closed end and an open end, said outer member having a discharge opening selectively communicable with the opening in the inner member for the passage of paste therethrough, cooperative means on the open ends of the members for preventing rotation thereof during the axial movement of the outer member relative to an opening position for operative communication of the discharge openings and locking means cooperatively arranged on said members for releasably retaining said outer member on the inner member in a closed and open position, said locking means including inwardly extending resilient detents on the outer member and outwardly extending abutment members formed on the inner member.

2. A dispensing closure cap for collapsible paste tubes comprising a cylindrically shaped hollow inner body having a closed end and an open end and having an outlet aperture therein and an external recess providing a rounded abutment intermediate the length thereof, a resilient sleeve fixed in the open end of said body and adapted to receive the neck of a collapsible tube, and a cylindrically shaped hollow outer body having a closed end and slidably receiving said inner body in its open end, said outer body having an outlet aperture therein selectively alignable with the outlet aperture in said inner body when said closure cap is open for the discharge of paste therethrough, and detents on said outer body resiliently engaging the abutment on said inner body to releasably hold said outer body in its closed and open positions relative to said inner body and maintain said bodies against complete axial separation.
